UNITED STATES PATENT OFFICE.

TALIESIN EVANS, OF LLANELLY, WALES.

PROCESS OF MANUFACTURING TIN PLATES.

1,414,347.

Specification of Letters Patent.

Patented May 2, 1922.

Application filed May 3, 1921. Serial No. 466,626.

To all whom it may concern:

Be it known that I, TALIESIN EVANS, a subject of the King of Great Britain and Ireland, residing at Gatcombe House, 27 5 Penalt Road, Llanelli, in the county of Carmarthen, Wales, have invented new and useful Improvements in the Processes of Manufacturing Tin Plates, of which the following is a specification.

10 This invention has reference to improvements in the process of manufacturing tin plates, and its chief objects are to simplify and reduce the cost of the process of manufacture and to attain as far as possible continuity of working.

According to the invention, the plates, after passing singly through the first pair of rolls are not returned to the furnace, but are passed again through the same rolls in pairs, 20 one on top of the other, a sufficient number of times to attain the required length. They then pass straight on to an automatic doubling device (or are doubled manually) which thus produces four sheets or four 25 thicknesses capable of being formed into separate sheets. From this they pass into a second furnace which is in two sections, each section provided with a door at each end. While one section is charged from the 30 doubling side, the other section is discharged from the opposite side, and vice versa therefore giving a constant supply of heated material to rolls number two. When the plates are withdrawn they are passed through this 35 second pair of rolls, first singly (that is, the four thicknesses together) until they are sufficiently increased in length, and then in pairs for two units of four thicknesses each. When the required length has been obtained, 40 the whole would be cut by a shears as required. It will thus be seen that there is no break in the continuity of operation and the various units such as furnaces, rolls, automatic doubling device and the like can be 45 kept constantly at work.

The accompanying drawings illustrate the invention.

Fig. 1 is a more or less diagrammatic view showing the position in line of the different 50 apparatus employed in the process of making tin-plates according to the invention.

Fig. 2 is a perspective view of the bar before rolling,

Fig. 3 is a side elevation of a plate rolled 55 therefrom,

Fig. 4 is a plan view of Fig. 3,

Fig. 5 is an edge view of two such plates superposed and rolled to twice the length and one-half the thickness,

Fig. 6 is a plan view of Fig. 5,

Fig. 7 is an edge view of Fig. 5 folded to half the length and then rolled to the same length as before rolling,

Fig. 8 is a plan view of Fig. 7,

Fig. 9 is an edge view, broken away, of 60 two units like Fig. 7 superposed and rolled to twice the length and half the thickness and;

Fig. 10 is a plan view of Fig. 9 showing 65 the points at which the strips are cut across to produce plates.

In the diagrammatic drawings, Figs. 2 to 10, inclusive, α represents the bar from which the plates are rolled and γ the plates in their successive rollings, being successively reduced in thickness and lengthened from the dimensions of Figs. 3 and 4 to those of Figs. 9 and 10.

Describing the invention with reference to the drawings and as applied for instance to 80 the manufacture of tin-plates of the size 28" by 20", sections are cut from iron or steel bar. These are heated in a suitable furnace

A which I prefer to be in two or more sections so that while one section is being discharged, heating can be continued in another section, thus ensuring a constant supply of material for the rolls B. The lengths are taken two at a time from the furnace by the "doubler" and are transferred to the roller- 85 man who passes them through the rolls B a sufficient number of times until the dimensions become about 28" by 20". When this point is reached, the plates are passed through the same rolls in pairs, that is, one 90 plate on the top of another, until they reach the desired length of about 56". They are then doubled manually or are passed across any automatic doubling device C the place of doubling and said device, if used, being 95 arranged next in succession in a straight line to the furnace A and rolls B aforementioned. The doubling of the plates produced four sheets or four thicknesses from which 100 separate sheets can be formed, and the doubled plates are then passed on in a straight line into a second furnace D. This furnace is in two sections, with doors at each end of the sections, so that the plates can be introduced at one side and removed from the 110

105

other. The sections are charged and discharged alternately so that the supply of heated material to the second pair of rolls E is continuous. This second pair of rolls 5 is in the same straight line with the foregoing apparatus and the plates are first passed through singly (that is, each unit of four thicknesses by itself) once or twice. Two units (each of four thicknesses) are then 10 laid one on top of the other and the two passed again through the rolls E until the length is increased to about 120''. This piece of 120'' in length is then run under a shears and cut in half, producing in practice 15 48 sheets, each 28'' by 20'' in size.

I claim:—

A process of manufacturing tin plates, consisting of the following steps; first, heating metallic bars and passing said heated bars through a pair of rolls, at first singly, 20 then in pairs, one superposed upon the other, to reduce them to plate form and attain the required length; secondly, doubling the resulting plates; thirdly, reheating them in a second furnace, and fourthly, passing the 25 doubled and heated plates through a second pair of rolls at first singly and then in pairs, one superposed upon the other.

TALIESIN EVANS.
